(57) **CLAIM**

The ornamental design for a combined dinosaur toy, as shown and described.

DESCRIPTION

FIG. 1 is a perspective view of a main body of a combined dinosaur toy, shown separately for ease of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a controller of the combined dinosaur toy shown separately for ease of illustration;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof;

FIG. 14 is a bottom plan view thereof;

FIG. 15 is a perspective view of the combined dinosaur toy showing my new design in a combined state;

FIG. 16 is another perspective view thereof;

FIG. 17 is a front elevational view thereof;

FIG. 18 is a rear elevational view thereof;

FIG. 19 is a left side elevational view thereof;

FIG. 20 is a right side elevational view thereof;

FIG. 21 is a top plan view thereof;

FIG. 22 is a bottom plan view thereof; and,

FIG. 23 is an enlarged view of the encircled portion in FIG. 1.

The dash-dash broken lines in the drawings depict portions of the combined dinosaur toy that form no part of the

(Continued)

claimed design. The dot-dash broken lines depict boundary of the enlarged portion and form no part of the claimed design.

The long-dash-short-dash-dot broken lines indicating an enlargement portion of the design form no part of the claimed design.
